UNITED STATES PATENT OFFICE.

TRUMAN J. PEET, OF MONTICELLO, IOWA.

CRIMPING-MACHINE.

1,241,145.

Specification of Letters Patent. Patented Sept. 25, 1917.

Application filed June 21, 1916. Serial No. 104,971.

To all whom it may concern:

Be it known that I, TRUMAN J. PEET, a citizen of the United States of America, and a resident of Monticello, Jones county, Iowa, have invented certain new and useful Improvements in Crimping-Machines, of which the following is a specification.

My invention relates to improvements in crimping machines, and the object of my improvement is to furnish mechanism adapted to crimp the open end of a hollow cylindrical body to adapt the latter for use as a receptacle or for other purposes. This object I have accomplished by the means which are hereinafter described and claimed, and which are illustrated in the accompanying drawings, in which:

Figure 1 is a front elevation of my crimping machine. Fig. 2 is an elevation of the rear of the forward frame part of the machine, with the parts of the machine which are connected thereto sectioned away. Fig. 3 is a like elevation showing certain moving parts in a different position. Fig. 4 is a rear elevation of said machine. Fig. 5 is a side elevation of the machine, with parts of the supporting structures for the mechanism sectioned away. Fig. 6 is an enlarged detail view of the two parallel crimping rollers as employed in crimping a cylindrical body, and showing the trip-lever about to be operated by the action of the upper crimping roller on the crimped body. Fig. 7 is a perspective view of the hollow cylindrical body before crimping, and Fig. 8 is a like view of said body after one end of it has been crimped.

Similar numerals of reference denote corresponding parts throughout the several views.

My improved device is primarily intended for use in crimping one open end of a hollow metallic cylinder to form the body of a basket or other receptacle.

The supporting frame of my machine comprises forward and rear corner standards 64 and 63. The standards 64 are fixedly connected in front by a plate 65, and the rear standards 63 are connected in the rear fixedly by a like plate 66. On each side, the forward and rear standards are connected by means of side plates 67, said forward, rear and side plates extending from the bottom of said standards only partly upwardly toward their tops.

An L-shaped bracket 5 is mounted on the

upper part of the forward plate 65 by means of bolts, and has in its upwardly turned limb a vertical bearing socket in which is rotatably mounted the depending spindle 9 of the pinion 10 with concaved beveled teeth. On the under surface of said pinion are crown teeth 11.

Referring to Fig. 5, the numeral 1 denotes a shaft having diminished parts mounted rotatably in bearing openings in cross-bars between the forward and the rear uprights respectively, and on the rearwardly extending part of said shaft are fixedly mounted a gear-wheel 6 and the belt-wheel 7, and also a loosely mounted belt-wheel 8. On the forwardly extending end of said shaft is removably mounted a longitudinally crimped forming-head 2 and on the front end of said head is fixed an axial spindle having an enlarged end 3, said spindle and its enlarged part being rotatably seated at the bottom of a T-shaped groove in said bracket 5 so that the forming head and its spindle may be dismounted from the bracket when desired. On the forward end of the forming-head 2 is a fixed gear 12 whose teeth mesh with the crown teeth 11 on the concave pinion 10.

The numerals 16 and 17 denote cross-bars mounted between the forward standards 64 and the rear standards 63 respectively. The cross-bar 16 has on its ends (not shown) diminished portions which are seated in grooves on the inner vertical edges of the standards 64 to allow the cross-bar to be swung upwardly a short distance. The rear cross-bar 17 is placed between two vertical hangers depending from either end of the cross-bar 18, the ends of the latter being diminished to likewise slide in grooves on the inner edges of the rear standards 63, and the cross-bar 17 has oppositely extending pintles 62 mounted to rock in bearing sockets in said hangers. A shaft 13 has diminished parts mounted in bearing orifices in the cross-bars 16 and 17, and carries on its rearwardly extending end a gear-wheel 15 meshing with the gear-wheel 6, the shaft 13 being arranged a little above the other shaft 1. On the forwardly extending end of the shaft 13 is detachably mounted a longitudinally grooved forming-head 14 adapted to mesh or coact with the forming-head 2 when the shaft 13 is moved downwardly. Between the upper ends of the forward standards 64 and the rear standards 63, re-

spectively, are fixed the cross-bars 22 and 19. A coiled compression spring 21 is engaged between the rear cross-bars 18 and 19, about alined pins 20, and serves to yieldingly push downwardly the cross-bar 18 with its connected pivotal cross-bar 17 to retain the gear-wheel 15 in mesh with the gear 6. A tension spring 23 is connected between the forward cross-bars 16 and 22 and tends to 10 yieldingly draw upwardly the cross-bar 16 to disengage the forming-head 14 from the forming-head 2 as shown in Fig. 5.

I have provided means for moving the forming-head 14 downwardly into coacting mesh with the forming-head 2. The numeral 35 denotes a medial vertical slot in the lower part of the forward plate 65, and a pedal lever 34 is passed rearwardly through said slot, and has its rear end pivotally connected to the eye on an eye-bolt 58 mounted in the lower end of the rear plate 66. Referring now to Figs. 2 and 3, in Fig. 2 is shown the position of the up and down movable roll 13 when disengaged from the other roll 1. The numeral 24 denotes a U-shaped bar, whose upper ends are bent forwardly and secured to the upper edge of the cross-bar 16 at opposite sides of the roll 13. A swinging arm 25 is pivotally connected at 26 to the middle of the loop of the U-shaped bar 24, and has its lower end pivotally connected at 30 to the upper end of the bar 31 whose lower end is provided with a fork 32 which bestrides the middle 35 of the lever 34, and is pivotally connected thereto by means of a pivot-bolt 33. A short swing-arm 28 has one end pivoted at 27 to the rear face of the plate 65 and has its other end pivoted at 29 to the lower part of the 40 swing-arm 25 above the pivotal connection 30 of the arm 31 therewith. When the said arms are in the positions shown in said Fig. 2, the spring 23 has moved the cross-bar 16 and U-shaped bar 24 upwardly, disengaging 45 said rolls from each other. To bring said rolls into mesh, the pedal-lever 34 is pushed downwardly thus shifting the pivotally-connected arms 25, 28 and 31 into overlapping alinement which places them on a dead 50 center and holds the roll 13 in its lowered position with the forming-heads 14 and 2 in mesh. A stop-pin 47 in the rear plate 65 prevents the said arms from swinging too far in one direction.

55 I have provided mechanism for throwing said arms from their position of dead center to permit the spring 23 to react and draw the former-head 14 out of mesh with the former-head 2. A short rock-shaft 44 is mounted in a bearing orifice in the lower part of the forward plate 65 and has a rock arm 51 fixed on its forward end. A short lever 53 is pivotally connected at 54 to the forward part of the frame, and has one end 60 pivoted to the upper end of a link 52 whose

lower end is pivotally connected to the outer end of the rock-arm 51. The free end 55 of the lever arm 53 is directed between the two forming-heads at one side thereof but so as to not interfere with their rotations.

70 Referring now to Figs. 2 and 3, the numeral 45 denotes a rock-arm fixed in an end of the shaft 44 and has a tappet body 46 threaded on its free end. A curved arm 43 is fixed on and depends from said shaft 44. The numeral 37 denotes a slide-plate having vertical slots 57 for the passage of securing screws 56 on which said plate is mounted to slide up and down on the rear face of the front plate 65. The lower end of the plate 37 has an angular foot 39. A vertical rod 40 is mounted on the plate 65 to slide up and down in staples 41, with its upper end under and adapted to engage the lower face of the foot 39, when lifted. The lower end 85 of the rod 40 has a fork 42 bestriding the end of the curved arm 43. The upper end of the slide plate 37 is bent over downwardly at 38, and said plate has an opening just below the tip of this bent-over part.

90 Referring now to Fig. 5, the numeral 49 denotes a hand-lever pivoted at its lower end between lugs 48 on the front plate 65. Both the front plate 65 and the rear plate 66 have horizontally alined bearing openings in which is movable a slide-rod 36 provided with a notch 59 in its upper edge. To the front end of the rod is pivotally connected the hand lever 49. A belt-shifting arm 61 is fixed on the rear end of the rod 36, and a coiled compression spring 60 is mounted on said rod between the arm 61 and the rear face of the rear plate 66, and tends to yieldingly shift the rod 36 rearwardly. The upper curved end 38 of the slide plate 105 37 rides upon the upper edge of the rod 36, since said rod passes through the opening in said slide-plate.

110 Operation: The moving parts of the machine being in the inoperative positions shown in Figs. 2, 3 and 5, when it is desired to operate the machine the pedal lever 34 is depressed, after the uncrimped cylinder 68 has been mounted upon the upper forming body 14. This draws the rock arms 25, 28 and 31 into the dead center position shown in Fig. 3, stretching the spring 23 and drawing the roller 13 to its lower position. The hand-lever 49 is then swung forwardly causing the shifting-arm 36 to shift a drive-belt, 115 (not shown), from the loose pulley 8 to the tight pulley 7, which places the intermeshed gears 6 and 15 in rotation with their forming-heads 2 and 14, thus crimping the cylinder 68 to the form shown in Fig. 8. When the rod 36 is drawn forwardly to said position, the bent tip 38 of the slide plate 37 drops into the notch 59, holding the rod in that position.

120 When the cylinder 68 is fully crimped 130

at 70 the operation of the machine is automatically stopped in the following manner:

The fold-over joint 69 of the cylinder, as shown in Fig. 6, as the crimping operation is completed, rotates into engagement with and pushes down the finger 55 of the lever 53 thus causing the link 52 to rock upwardly the rock-arm 51, rocking the shaft 44 to swing the tappet body 46 against the swing 10 arm 31. The arms 25, 28 and 31 are then swung off their dead center so that the spring 23 can react to rock upwardly the forming-head 14 so that the crimped cylinder may be dismounted therefrom. Simultaneously, the rock-arm 43 pushes up the slide-rod 40 against the foot 39 on the slide-plate 37, thus pushing up the slide-plate and disengaging its bent-over end 38 from the rod 36 so that the spring 60 may react and 20 shift the driving-belt back upon the loose pulley.

It is to be understood that various changes may be made in the forms, arrangement and operation of the coacting parts of my machine, without departing from the principles of the invention or the scope of its protection.

Having described my invention, what I claim as new, and desire to secure by Letters 30 Patent, is:

1. In a crimping-machine, a rotatable positively-driven crimping-head, a counterpart crimping-head movable into coaction therewith, mechanism connected yieldingly 35 and resiliently to said movable crimping-head for shifting it into coaction with the other crimping-head and containing co-acting locking elements arranged to lock it therewith, comprising a pivoted lever, a reciprocating bearing in which said counterpart crimping-head is rotatably mounted, an arm pivoted at one end to said bearing, a link pivoted at one end to said lever and at the other end to the adjacent end of said arm, a 40 fixed support, another arm pivoted at one end to said support and pivoted at the other end to the first-mentioned arm, whereby said bearing is held fixedly when the pivotal connections of said parts are shifted to a dead 45 center, mechanism connected to and adapted to act on said shifting-mechanism to unlock said shifting-mechanism and allow the resilient connection to react and shift the movable crimping-head out of coaction with the 50 other crimping-head, and means for stopping the rotation of said crimping-heads when out of coaction with each other, said last-mentioned means being connected to 55
2. In a crimping-machine, a supporting-frame, rotatable coacting counterpart crimping-heads having circumferential longitudinal flutings, one being movable to and from the other, the said movable crimping-head having crimping flutings on its end, and a third rotatable crimping-head mounted at an angle to and counterpart 60 of the fluted end of said movable crimping-head and also adapted to coact with the end flutings thereof when the movable head is moved toward it and the other crimping-head to bend over and crimp an 65 edge or a plate between them.
3. In a crimping-machine, a supporting frame, rotatable coacting counterpart crimping-heads, one movable to and from the other, the other being positively driven, 70 driving-connections between said crimping-heads, a third crimping-head adapted to coact with said movable head when the latter is in coaction with the other head, driving-connections between said other head and said 75 third crimping-head, means for shifting said movable crimping-head into and out of coaction with the other crimping-heads, said means including an element positioned near the movable crimping-head and movable by 80 engagement with a moving projecting part of the article being crimped to operate the means in swinging said movable head out of coaction with the other heads.
4. In a crimping-machine, a rotatable 85 crimping-head with corrugated convex outer end, and a rotatable crimping head of concave conoidal form coacting with the end of the first-mentioned crimping-head, said crimping-heads having axes disposed angularly 90 relative to each other.
5. In a crimping-machine, a rotatable corrugated forming-head, another rotatable corrugated forming-head mounted to coact with an extremity of the first-mentioned 105 head to shape a plate inserted between them, the second-mentioned head and the end of the first-mentioned head being counterparts to form the plate into a hollow body with an inwardly-bent corrugated edge, said forming-heads having axes disposed angularly 110 relative to each other.

Signed at Monticello, Iowa, this 6th day of June, 1916.

TRUMAN J. PEET.
